AUXILIARY TABLE TOP

Edwin E. Czak, Elyria, Ohio

Application February 3, 1947, Serial No. 726,167

2 Claims. (Cl. 311—106)

1

This invention relates to tables of the type used as card tables. Such tables are usually provided with folding legs and are of such size that while they may be conveniently used for playing cards they are not large enough to permit refreshments to be served upon the card tables.

Therefore it is one object of the invention to provide an auxiliary table top adapted to be placed upon the top of a card table of conventional size and thus provide sufficient space for refreshments to be served without crowding the table to such an extent that persons using the table will interfere with each other while eating.

Another object of the invention is to provide an auxiliary table top having depending strips constituting a retainer which is concentric with the table top and will fit about the top of the table and effectively prevent the auxiliary table top from being accidentally shifted out of its proper position upon the table and being tilted by the weight of dishes placed on the auxiliary table top.

Another object of the invention is to provide an auxiliary table top formed of sections hinged to each other so that the auxiliary table top may be folded and conveniently stored in a small space when not in use.

Another object of the invention is to provide an auxiliary table top having springs extending across meeting edges of its sections and so located with respect to the hinges connecting the sections that pull of the springs will hold the sections in an extended position for use and also yieldably hold the sections folded.

Another object of the invention is to provide an auxiliary table top which is simple in construction and capable of being manufactured at low cost.

The invention is illustrated in the accompanying drawings wherein:

Fig. 1 is a top plan view showing the auxiliary table top applied to a table in position for use.

Fig. 2 is a side elevation of the auxiliary table top and the table upon which it rests.

Fig. 3 is a view similar to Figure 2 taken at right angles thereto.

Fig. 4 is a fragmentary view showing the auxiliary table top in section along the line 4—4 of Figure 1, the folded position of the top sections being indicated by dotted lines.

Fig. 5 is a fragmentary view showing a portion of the auxiliary table top in bottom plan.

Fig. 6 is a fragmentary sectional view showing a modified construction.

The table which is indicated in general by the

2

numeral 1 is a card table of conventional construction and has the usual square top 2 and foldable legs 3. A table of this type is large enough for four persons to sit at sides thereof and play cards but when refreshments are to be served there is not sufficient space to place plates, cups and saucers, and other dishes containing food upon the table top, and the table is often overcrowded.

In order to overcome this overcrowding I have provided an auxiliary table top 4 which is formed of companion sections 5 of such dimensions that they form a square table top which is of appreciably greater size than the top 2 of the card table 1. The sections 5 of the auxiliary table top have been shown formed of laminated sheets 6 and each is bordered by strips 7 formed of stiff wood and provided with inwardly extending flanges 8 which fit under the laminated sheets so that the auxiliary top will be braced and a neat appearance imparted to it. While it has been stated that the top sections 5 are formed of laminated sheets it will be understood that invention is not limited to this specific construction.

Against under faces of the top sections 5 is mounted a frame 9 which is square and of slightly greater dimensions than the top of the card table so that when the auxiliary top is placed upon the top 2 of the card table the frame 9 may fit about the top of the card table, as shown in Figure 1. The frame 9 is formed of wooden strips 10 and 11 and upon referring to Figures 4 and 5 it will be seen that the strips 11 terminate flush with inner side edges of

the top sections 5 and have abutting engagement with each other when the auxiliary table top is in an extended position for use. Hinges 12 connect abutting ends of the strips or bars 11 and are secured against under faces thereof so that the top sections 5 may be swung from an extended position for use to a folded position close against each other as indicated by dotted lines in Figure 4.

Hooks 13 which are struck from plates 14 extend downwardly from inner end portions of the strips or bars 11 to which the plates are secured by screws 15, and to these hooks are attached ends of spring 16 which are under tension and serve to exert pull upon the hooks. When the top sections 5 are in the extended position the springs are above the hinges and serve to hold the bars 11 in abutting engagement with each other and maintain the top sections extended. When the top sections are swung downwardly to a folded position the springs are below the hinges and serve to hold the top sections in the folded

position for use.

Fig. 4 is a fragmentary view showing the auxiliary table top in section along the line 4—4 of Figure 1, the folded position of the top sections being indicated by dotted lines.

Fig. 5 is a fragmentary view showing a portion of the auxiliary table top in bottom plan.

Fig. 6 is a fragmentary sectional view showing a modified construction.

The table which is indicated in general by the

condition. Leaf springs 17 are secured to under faces of the bars 10 midway the length thereof and have free end portions which project upwardly close to inner side faces of these bars. When the top sections 5 are moved to the extended position and the auxiliary table top set in place upon the top of the card table the leaf springs engage confronting side edge faces of the card table top and frictionally grip the same so that the auxiliary table top will be held in place and prevented from shifting out of a position in which the auxiliary table top is centered with respect to the card table top. In order to remove the auxiliary top it is merely necessary to grasp it and exert upward pull to dislodge it from the card table and the two sections 5 may then be moved to a folded position and the auxiliary top then placed in a closet against a wall thereof until again needed.

Instead of using the leaf springs 17 to hold the auxiliary table top upon the card table a suitable number of set screws 18 may be threaded through openings 19 formed through the bars 10 of the auxiliary top sections, as shown in Figure 6, and similar set screws also passed through the bars 11 if so desired. Each of the set screws has a turning head 20 at its outer end and to its inner end is swiveled a foot 21 which is forced against the confronting edge face of the card table top and firmly grips the same to hold the auxiliary table top in place upon the card table.

Having thus described the invention, what is claimed is:

1. An auxiliary table top of appreciably greater dimensions than the top of a main table upon which the auxiliary table top is to be placed, said auxiliary table top comprising companion sections having adjoining side edge faces abutting when in an extended position, an open frame for fitting about the top of a main table carried by the auxiliary top and consisting of side bars extending longitudinally of the top sections and end bars extending transversely of the top sections, hinges carried by inner ends of the end bars and mounting the top sections for swinging movement from an extended position downwardly to a folded position close to each other, and springs extending in bridging relation to the top sections and secured to inner side edge portions

thereof and serving to yieldably hold the said top sections in extended and folded positions.

2. An auxiliary table top of appreciably greater dimensions than the top of a main table upon which the auxiliary table top is to be placed, said auxiliary table top comprising companion sections having adjoining side edge faces abutting when in an extended position, an open frame for fitting about the top of a main table carried by the auxiliary top and consisting of side bars extending longitudinally of the top sections and end bars extending transversely of the top sections, hinges carried by inner ends of the end bars and mounting the top sections for swinging movement from an extended position downwardly to a folded position close to each other, plates secured against under faces of inner side edge portions of the top sections adjacent the end bars, hooks extending downwardly from said plates, and helical springs bridging the inner side edges of the top sections and having eyes at their ends engaged with the hooks, said springs having movement past the hinges as the top sections are swung to extended and folded positions and serving to yieldably hold the top sections in the adjusted positions.
